US00D889653S

(12) **United States Design Patent** (10) **Patent No.:** **US D889,653 S**
(45) **Date of Patent:** **** Jul. 7, 2020**

(54) **STENT HAVING TAPERED STRUTS**

6,077,297 A 6/2000 Robinson et al.

6,083,257 A 7/2000 Taylor et al.

6,090,140 A 7/2000 Gabbay

6,214,036 B1 4/2001 Letendre et al.

6,264,691 B1 7/2001 Gabbay

6,267,783 B1 7/2001 Letendre et al.

6,368,348 B1 4/2002 Gabbay

6,419,695 B1 7/2002 Gabbay

6,458,153 B1 10/2002 Bailey et al.

6,468,660 B2 10/2002 Ogle et al.

6,488,702 B1 12/2002 Besselink

6,517,576 B2 2/2003 Gabbay

6,533,810 B2 3/2003 Hankh et al.

6,582,464 B2 6/2003 Gabbay

6,610,088 B1 8/2003 Gabbay

6,623,518 B2 9/2003 Thompson et al.

6,652,578 B2 11/2003 Bailey et al.

6,685,625 B2 2/2004 Gabbay

6,716,244 B2 4/2004 Klaco

6,719,789 B2 4/2004 Cox

6,730,118 B2 5/2004 Spenser et al.

6,783,556 B1 8/2004 Gabbay

6,790,230 B2 9/2004 Beyersdorf et al.

6,814,746 B2 11/2004 Thompson et al.

6,830,584 B1 12/2004 Seguin

6,869,444 B2 3/2005 Gabbay

6,893,460 B2 5/2005 Spenser et al.

6,908,481 B2 6/2005 Cribier

6,951,573 B1 10/2005 Dilling

7,018,406 B2 3/2006 Seguin et al.

7,025,780 B2 4/2006 Gabbay

7,137,184 B2 11/2006 Schreck

7,147,661 B2 12/2006 Chobotov et al.

7,160,322 B2 1/2007 Gabbay

7,195,641 B2 3/2007 Palmaz et al.

7,247,167 B2 7/2007 Gabbay

7,267,686 B2 9/2007 DiMatteo et al.

7,276,078 B2 10/2007 Spenser et al.

7,311,730 B2 12/2007 Gabbay

7,320,704 B2 1/2008 Lashinski et al.

7,329,278 B2 2/2008 Seguin et al.

7,374,573 B2 5/2008 Gabbay

7,381,218 B2 6/2008 Schreck

7,381,219 B2 6/2008 Salahieh et al.

7,452,371 B2 11/2008 Pavnik et al.

7,510,572 B2 3/2009 Gabbay

7,510,575 B2 3/2009 Spenser et al.

7,524,331 B2 4/2009 Birdsall

7,534,261 B2 5/2009 Friedman

RE40,816 E 6/2009 Taylor et al.

7,585,321 B2 9/2009 Cribier

7,628,805 B2 12/2009 Spenser et al.

7,682,390 B2 3/2010 Seguin

(21) Appl. No.: **29/604,136**

(22) Filed: **May 15, 2017**

(51) LOC (12) Cl. **24-03**

(52) U.S. Cl.

USPC **D24/155**

(58) **Field of Classification Search**

USPC **D24/155**

CLAIM

The ornamental design for a stent having tapered struts, as shown and described.

DESCRIPTION

The present application is related to U.S. Design patent application Ser. No. 29/604,134, filed concurrently herewith, and U.S. Design patent application Ser. No. 29/604,160, filed concurrently herewith, and U.S. Design application Ser. No. 29/604,139, filed concurrently herewith, and U.S. Design patent application Ser. No. 29/604,148, filed concurrently herewith, the entire disclosures of all of which are incorporated herein by reference.

FIG. 1 is a front perspective view of a stent having tapered struts according to Embodiments 1-4 of our new design; FIG. 2 is a front elevational view of Embodiments 1-4 thereof; FIG. 3 is a rear elevational view of Embodiments 1-4 thereof; FIG. 4 is a right side elevational view of Embodiments 1-4 thereof; FIG. 5 is a left side elevational view of Embodiments 1-4 thereof; FIG. 6 is a top plan view of Embodiments 1-4 thereof; FIG. 7 is a bottom plan view of Embodiments 1-4 thereof; FIG. 8 is an enlarged front elevational view of a portion of FIG. 2; FIG. 9 is an enlarged front elevational view of section C of FIG. 8, which is an enlarged strut of the stent having tapered struts according to Embodiment 1;

FIG. 10 is an enlarged front elevational view of section C of FIG. 8, which is an enlarged strut of the stent having tapered struts according to Embodiment 2;

FIG. 11 is an enlarged front elevational view of section C of FIG. 8, which is an enlarged strut of the stent having tapered struts according to Embodiment 3; and,

FIG. 12 is an enlarged front elevational view of section C of FIG. 8, which is an enlarged strut of the stent having tapered struts according to Embodiment 4.

FIG. 8 is an enlarged view of a section of FIG. 2 and illustrates a complete cell of the stent, as well as one-half cell directly above the complete cell according to Embodiments 1-4. The complete cell of the stent includes four struts (strut 1-4) that together form the complete cell. The one-half cell includes only two struts (struts 5-6).

An enlarged view of a single strut (strut 1) of the complete cell is shown in FIGS. 9-12, according to respective Embodiments 1-4, and each single strut 1 includes an first upper end and a lower end. The shapes or profiles of the remaining struts in the enlarged views of FIG. 8 are mirror images of strut 1 across an x-plane or a y-plane, as discussed in further detail below.

In FIG. 8, according to Embodiments 1-4, a respective second strut (strut 2) is shown positioned to the left of strut 1. Strut 2 is a mirror image of strut 1 taken across a plane that extends along a y-axis, such that strut 2 has an identical shape or profile as strut 1. Strut 1 and strut 2 together form an upper one-half of the complete cell.

In FIG. 8, according to Embodiments 1-4, a third strut (strut 3) is shown positioned directly below strut 1 and extends from the lower end of strut 1. Strut 3 has a shape or profile that is a mirror image of strut 1 taken across a plane that extends along an x-axis through the lower end of strut 1. In FIG. 8, according to Embodiments 1-4, a fourth strut (strut 4) is positioned to the left of strut 3. Strut 4 has a shape or profile that is a mirror image of struts 1 and 3 taken across a plane that extends along the y-axis. Struts 3 and 4 together form a lower one-half of the complete cell, such that taken together, struts 1, 2, 3, and 4 form the complete cell.

In FIG. 8, according to Embodiments 1-4, a fifth strut (strut 5) is positioned above strut 1 and extends from the upper end of strut 1. Strut 5 has a shape or profile that is a mirror image of strut 1 taken across a plane that extends along an x-axis through the upper end of strut 1. In FIG. 8, according to Embodiments 1-4, a sixth strut (strut 6) is positioned to the left of strut 5. Strut 6 has a shape or profile that is a mirror image of struts 3 and 5 taken across a plane that extends along the y-axis. Together, the struts 5 and 6 form one-half of a complete cell.

A similar pattern of the complete cell and one-half cell extends around the circumference of the stent in each of Embodiments 1-4, which in turn, respectively correspond to the enlarged stent sections of FIG. 8, as well as the single struts shown in FIGS. 9-12. Each of the remaining struts in the complete cell and the one-half cell pattern that are oriented in the same position as respective struts 1, 2, 3, 4, 5 and 6 discussed above, will possess the same shape or profile as respective struts 1, 2, 3, 4, 5 and 6 discussed above. In Embodiments 1-4, the complete cell and one-half cell pattern shown in FIG. 8 is repeated an additional eight (8) times around the circumference of the stent.

The broken lines shown in the drawings illustrate environmental structure and form no part of the claimed design. The dot-dash lines represent boundary lines and form no part of

the claimed design. It is to be understood that the claimed design extends to but does not include the defined boundary.
